VISE AND ANGLE SINE PLATE

William C. Keebler, Washington, D. C.

Application March 1, 1946, Serial No. 651,138

11 Claims. (Cl. 90—60)

1

My invention relates to certain improvements in vises and sine plates and they are a type that is precision built and the jaws open and close by means of a screw and handle, one of the jaws remaining stationary and the other slides back and forth. The vise is made to fit on the sine plate and is held securely in position by means of dowel pins and screws. The vise can also be turned universally on the sine plate and locked on any angle between zero (0) and 360 degrees.

One object of the invention is to provide a simple way to clamp high grade tool work in any angle desired. The sine plate has two openings and can be blocked open with precision measuring blocks producing very accurate angles. Blocking open both sine bar openings at one time produces a compound angle. The vise can also be swiveled to any desired angle while both the sine bar openings are blocked open.

In the accompanying drawings:

Figure 6 is a view of my improved vise and compound angle sine plate. This view is a view of the whole thing completely assembled.

Figure 7 is a view of piece 18.

Figure 8 is a view of piece 33.

Pieces 18 and 35 are made of high grade tool steel which is hardened and drawn to its proper degree of hardness and is precision ground and precision lapped to a very close tolerance. Piece 33 is also sawed open on one side and nearly through on the other side with a grinding wheel, so that screw 21 can be tightened so that piece 33 is locked on piece 18 and can be unlocked by loosening screw 21 slightly. Also piece 18 and piece 33 could be made as shown in Figure 9.

Figure 9 is a view of pieces 34 including pieces 13 and 32. Piece 34 is made of high grade tool steel which is hardened and drawn to its proper degree of hardness and is precision ground and lapped to the required size. Whereas pieces 13 are a snug fit on each end of piece 34. And the locking and unlocking device is produced by tightening and loosening set screws 32.

Figure 10 is a plan or top view of piece 15.

Figure 11 is an end view of piece 15.

Figure 12 is a front view or elevation of piece 15.

Piece 15 is made of high grade nonshrinkable tool steel and is hardened and drawn to its proper degree of hardness and is precision ground and lapped to its required size.

Figure 1 is a side view of the vise and sine plate completely assembled.

Figure 2 is an end view of the vise and sine plate completely assembled.

2

Figure 3 is a plan or top view of the vise assembled to the sine plate. The cutaway section of the vise shows the graduation marks on the sine plate.

Figure 4 is a side elevation or view of the sine plate showing the opening blocked open with toolmakers' precision blocks. The precision blocks are sometimes made to measure in millionths of an inch. When blocks of this type are used to block open the sine plate that produces angles to measure in degrees, minutes and seconds.

Precision blocks 23 and 24, Figure 4, are used to block open the sine plates to the desired angle. The blocks are very accurate to within millionths of an inch. The center distance between these pins is supposed to be very accurate also, say, to within one tenth of a thousandth of an inch, therefore, by blocking open the sine plate as shown in Figure 4. If the center distance is exactly 5.000 inches that would produce a triangle of 30 degrees and no minutes and no seconds. In Figure 5, if the center distance between pins was 2.5000 inches that would also produce a triangle of 30 degrees. This is proven by multiplying the sine of the angle of 30 degrees which is .5000" times the hypotenuse which equals .5000" times 2.500" which equals 1.250 inches as shown in Figure 5.

Figure 5 is an end view which shows the other opening which is blocked open with high grade precision blocks.

As to the design and construction of the sine plate and vise all pieces and parts are made of a high grade nonshrinkable tool steel and are hardened and drawn to their proper degree of accuracy, which produces a beautiful piece of valuable art in high grade tool room work.

Jaws 3 and 4 are held in place by screws 22 and dowel pins 21. This means the jaws can be removed and reground.

Pieces 24 and 25 are screwed and doweled on to piece 2, the sliding jaw. The sliding jaws move back and forth by screw 5 over the hardened and lapped square ways.

The cutaway section and the zero graduation 20, is to use to swivel the vise to any desired angle on the sine plate looking at the graduation lines on the sine plate as shown in Figure 3. The vise can be turned on the sine plate to any desired angle by removing one of the capscrews 19 and both dowel pins 10, Fig. 1.

Piece 6 is a removable hardened and ground threaded nut which is a force press fit into piece 1, Figure 6. Screw 5 is a hardened and ground and lapped screw that fits into piece 6. Piece

7 is a dowel pin that fits in the end of screw 5 and handle 8. Knob 9 fits into handle 8. Piece 15 has graduation lines cut on it as shown in Figure 3, and is precision ground and lapped to fit onto pieces 12, 13, and 34. Pieces 12 and 13 are so spaced in whole inches in length to allow the use of the sines, cosines and tangents, etc., of trigonometry tables; for instance, say 5 inches in 4 decimal points as thus 5.0000 inches. Pieces 13 are made as shown in Figure 9 and fit onto the ends of piece 34. The inside and outside diameters of pieces 34 and 13 must be very accurate and must measure to within and not less than 4 decimal points or to within tenths of a thousandth of an inch. When the long or lengthwise side of the sine plate is opened, screws 32 can be tightened and lock the sine plate to the desired amount of tightness. When the bottom section or short sidewise side of the sine plate is opened screws 21 can be tightened on pieces 33 to allow for the exact amount of tightness required or vice versa. In other words set screws 37 may be used in the ends of both pins to tighten and loosen the opening and closing devices, or split bushings as shown in Figure 8, can be used on both the pins 18 and 34.

The center distance of the pins on the lower section of the short side must be a known size in inches. The reason for that is the plain, simple sine bar rule, so that the sine and cosines, tangents, etc. can be used, having in mind always that the center distance is the hypotenuse of the angle and the center distance multiplied by the sine of the angle produces the amount of the measurement that the blocks should measure to produce the required angle. Pieces 13 are screwed onto piece 14 and piece 34 is screwed onto piece 15 thereby producing a hinge type design. Pieces 33 are screwed onto piece 16 and 18 is screwed onto piece 15 which also produces a hinge type design. The bottom of piece 16 may be serrated or corrugated if so desired.

The sine plate consists of 3 rectangular steel plates 14, 15 and 16, that are hinged together by pins 18 and 34 that are fastened onto the ends and sides by the pins and bushings. Bushings 13 are fastened onto one end of the top plate, the short pin 34 is fastened onto one end of the middle plate. The long pin is fastened onto one side on the bottom of the middle plate. The long bushings 33 are fastened onto one side on the bottom of plate. These bushings 33 and 13 have ground and lapped holes in them that fit on the ends of the pins 18 and 34. Two set screws 32 fit in the ends of the pins 13. Two small capscrews 21 fit on each bushing 33. Bushing 33 is split open on one side and nearly through on the other side to allow for cap screws 21 to close the bushings around the pins.

Dowel pins 26 and capscrews 27 hold plates 24 and 25 onto the sides of vise jaw 2. Pieces 24 and 25 fit onto the sides of the sliding jaw piece 2.

Set screw 35 screws into piece 2, and has a round point that fits into the groove on the end of the screw 5.

Pieces 36 are two hardened and ground and lapped flat keys that hold piece 2 down onto the ways on piece 1. Pieces 37 are two cap screws that fit into pieces 36, 38 and 2. Piece 38 is hardened and ground and lapped flat keys that fit between pieces 36 and 2 by capscrews 37. The two flat keys are fastened onto the sliding vise jaw 2 and holds the vise jaw downwardly, how-

ever, not too tight as the vise jaw has to slide back and forth.

I claim:

- 5 1. A sine plate including a rectangular base, an intermediate rectangular plate, an upper rectangular sine plate, said base and intermediate and upper plates having the same rectangular dimensions, hinge connecting means between the intermediate plate and base along the edges at one side of said members, and hinge connecting means between said intermediate plate and the upper sine plate along edges at a side at right angles to the side of the hinge connection between the intermediate plate and base whereby
- 10 15 the sine plate may be pivoted to any desired angle or simultaneously to two angles at right angles with respect to each other, both of said hinge connecting means being positioned wholly within the confines of the areas of the base and intermediate and upper plates so that when the plates are in closed position with respect to each other the peripheral edges of these hinge members will constitute a rectangular block providing vertical walls on each of the four sides thereof.
- 20 25 2. A sine plate including a rectangular base, an intermediate rectangular plate, an upper rectangular sine plate, said base and intermediate and upper plates having the same rectangular dimensions, hinge connecting means between the intermediate plate and base along the edges at one side of said members, hinge connecting means between said intermediate plate and the upper sine plate along the edges at a side at right angles to the side of the hinge connection between the intermediate plate and base, both of said hinge connecting means being positioned wholly within the confines of the areas of the base and intermediate and upper plates so that when the plates are in closed position with respect to each other the peripheral edges of these hinge members will constitute a rectangular block providing vertical walls on each of the four sides thereof.
- 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965

4. A sine plate and vise combination comprising, a supporting base, a sine plate, a pivotal

connection between corresponding side edges of said base and sine plate, an adjustable work holding vise, a vertically pivoted connection between said sine plate and said vise so that the vise may be turned over the upper plane of the sine plate, and means for fastening said vise in any desired angularly adjusted position with respect to the sine plate about its pivotal connection therewith.

5. A sine plate and vise combination comprising, a supporting base, a sine plate, a pivotal connection between corresponding side edges of said base and sine plate, an adjustable work-holding vise, a vertically pivoted connection between said sine plate and said vise so that the vise may be turned over the upper surface of the sine plate, a graduated circular scale on the upper surface of the sine plate centered with respect to said pivotal connection, an index mark on the vise for cooperating with said scale on the sine plate, and means for fastening said vise in any desired angularly adjusted position with respect to the sine plate about its pivotal connection therewith.

6. A sine plate and vise combination comprising a rectangular sine plate having a plane upper surface, a support therefor, and a pivotal connection between one of the edges of said plate and said support; an adjustable work-holding vise having a plane lower base surface for engaging said upper surface of the sine plate, and means for securing said vise in adjusted positions on said sine plate.

7. A sine plate and vise combination comprising a rectangular sine plate having a plane upper surface, a support therefor, and a pivotal connection between one of the edges of said plate and said support; an adjustable work-holding vise having a plane lower base surface for engaging said upper surface of the sine plate, a vertical pivotal connection between the vise and sine plate permitting the vise to be turned with respect to the sine plate, and means for securing said vise in rotary adjusted positions on said sine plate.

8. A sine plate and vise combination comprising a rectangular sine plate having a plane upper surface, a support therefor, and a pivotal connection between one of the edges of said plate and said support; a vise having a plane lower base surface for engaging said upper surface of the sine plate, said vise having a fixed jaw at one end, a cooperating movable jaw, a manually operated screw for moving the same, side grooves in the base, plates on the ends of said movable jaw having their lower ends engaging in said grooves in the base, and means for securing said vise in adjusted positions on said sine plate.

9. A sine plate and vise combination comprising a rectangular sine plate having a plane upper surface, a support therefor, and a pivotal connection between one of the edges of said plate and said support; an adjustable work-holding vise having a plane lower base surface for engaging

said upper surface of the sine plate, means for securing said vise in a normal fixed position on said sine plate including positioning pins and connecting set screws, and means for securing said vise in adjusted positions on said sine plate.

5 10. A sine plate and vise combination in accordance with claim 2 wherein the hinge connecting means comprises cylindrical rods with reduced cylindrical ends, cooperating tubular end elements on said reduced cylindrical ends of the type shown and described, all said hinge parts so positioned that their outermost peripheries will coincide with the planes of their respective vertical side walls of the block as constituted by the 15 edges of the base and plates, and means for adjusting the hinge tension and block relationship of the base and plates with respect to each other.

11. A sine plate including a rectangular base, an intermediate rectangular plate, an upper rectangular sine plate, hinge connecting means between the intermediate plate and base along the edges at one side of said members, hinge connecting means between said intermediate plate and the upper sine plate along edges at a side 20 25 at right angles to the side of the hinge connection between the intermediate plate and base, a vise supported on said sine plate, said vise including a base plate having a pair of parallel slots therethrough extending longitudinally thereof and equally spaced from the sides of the base 30 35 plate, a pivotal connection between said sine plate and vise base plate in a mid position between the slots therethrough so that the vise base plate may be rotated over the surface of the sine plate, said vise base having a fixed jaw secured to one end thereof, a cooperating movable jaw having guide members engaging in said slots through the base plate of the vise, means for moving the movable jaw along the vise base plate toward and away from said fixed jaw including an operating screw having one end thereof swivelly connected therewith, a fixed block mounted on the other end of said vise base plate and having a threaded engagement with said operating screw, 40 45 and means for securing said vise base plate in any desired angularly rotated position with respect to the sine plate.

WM. C. KEEBLER.
